UNITED STATES PATENT OFFICE

168,214

RADIO PANEL

Luther W. Couillard, Cedar Rapids, Iowa, assignor to Collins Radio Company, Cedar Rapids, Iowa, a corporation of Iowa

Application May 7, 1951, Serial No. 15,092

Term of patent 14 years

(Cl. D26—1)

To all whom it may concern:

Be it known that I, Luther W. Couillard, a citizen of the United States, residing at Cedar Rapids, State of Iowa, have invented a new, original, and ornamental Design for a Radio Panel, of which the following is a specification, reference being had to the accompanying drawing, forming a part hereof.

Figure 1 is a front view of my radio panel,
Figure 2 is a top view of the radio panel; and
Figure 3 is a sectional view taken on line 3—3
of Figure 2.

I claim:

The ornamental design for a radio panel, as shown.

LUTHER W. COUILLARD.
